UNITED STATES PATENT OFFICE.

FREDERICK SCHRUMPF, OF CHICAGO, ILLINOIS.

STOP-COCK.

SPECIFICATION forming part of Letters Patent No. 243,731, dated July 5, 1881.

Application filed February 23, 1881. (Model.)

To all whom it may concern:

Be it known that I, FREDERICK SCHRUMPF, of Chicago, in the county of Cook and State of Illinois, have invented a certain new and 5 useful Improvement in Stop-Cocks, of which the following is a specification.

My invention relates to stop-cocks for shutting off the water in houses and for hydrants; and it consists in the peculiar novel devices 10 and combinations of devices embodied in my stop-cock, as fully hereinafter explained, and pointed out by the claims.

In the accompanying drawings, forming a part hereof, Figure 1 is a vertical section of 15 the stop-cock, the connections with the same being shown in elevation, and the cock being turned to shut off the supply of water and to allow the water in the house-pipes to run off into the sewer; Fig. 2, a top view of the 20 stop-cock, the dotted lines indicating the direct passage for the water-supply; and Fig. 3, a bottom view of the cock or valve.

Like letters denote corresponding parts in all three figures.

25 A is the case of the stop-cock, which has a tapered bore, as shown, and a screw-cap, a.

To opposite sides of the case A are connected the water-pipes B C, the pipe B being connected with the water-main in the street, 30 while the pipe C is connected with the system of pipes in the house.

From the bottom of the case A projects downwardly a short pipe, D, surrounded by a box, E. Out of the side of this box, above 35 the lower end of the pipe D, extends a pipe, F, which is connected with the sewer G.

H is the cock or valve, which is tapered to fit the bore of the case A. It has a water-passage, b, extending horizontally straight 40 through the same on a level with the pipes B C, and at right angles to the passage b the valve has a curved passage, c, extending from the side of the valve on a level with the pipe C and through to the bottom of the valve, 45 connecting with the waste-pipe D, and thus making a three-way cock or valve. The valve is provided with shoulders d d' on its bottom, which strike a stud, e, projecting upwardly from the bottom of the valve-case. The shoul- 50 ders and stud limit the movement of the

valve. When water is being supplied to the house the valve is turned so as to bring the passage b in line with the pipes B C, one of the shoulders d d' resting against the stud e. The water then flows from the pipe B through 55 the stop-cock to the pipe C, and thence into the system of pipes in the house, all connection with the waste-pipe D being cut off. Now, when it is desired to shut the water off from the house, the valve is turned until the 60 other shoulder strikes the pin e. This movement closes the pipe B and brings the passage c into connection with the house-pipe C, as shown in Fig. 1. The water in the system of house-pipes then runs back into the stop-cock 65 and passes out through the pipe D, box E, and pipe F into the sewer G.

It will be seen that, the water having a free outlet into the sewer, and the pipes D and F being of the same size, or nearly the same 70 size, as the pipes B C, the water will run quickly out of the house-pipes before it can possibly freeze. The water being carried off by the sewer, instead of being allowed to soak into the ground beneath the cellar-floor, no 75 dampness can result, and other objections to the method heretofore employed will be overcome. The water-seal formed by the box E prevents the sewer-gas from entering the cock or water-pipes. 80

The valve-stem f projects up through the cap a, and is squared to receive the socket I. This socket is attached to the lower end of the rod K, forming therewith the turn-key for operating the valve. Heretofore the weight 85 of this turn-key has been wholly supported by the valve-stem, and that weight, together with the pressure brought to bear upon such turn-key, has often forced the valve into the bore of the case and caused it to stick so that it 90 could not be turned. This objection I overcome by making the stem f and socket I of such relative length that the socket will rest on the cap a, as shown, such cap being provided with a central annular projection, g, for 95 that purpose.

These same devices can be applied to hydrants without material modification, as will be readily understood.

What I claim as my invention is—

1. In a stop-cock, the combination, with casing A, having water-pipe branches B C, bottom waste-pipe, D, and screw-cap *a*, of the tapered valve-plug H, having horizontal passage *b*, and the curved downward leading passage *c*, and arranged to either connect pipes B C, or with a quarter-turn to connect pipes C and D, all substantially as and for the purpose described and shown.
- 10 2. In a stop-cock for the purpose set forth, the combination, with the casing A, having screw-cap *a*, and the valve-plug H, having
- stem *f*, of the turn-key socket I, resting upon the screw-cap *a*, substantially as and for the purpose set forth.
3. In a stop-cock, the combination, with valve-casing A, having bottom nozzle, D, of box E, secured to said casing over nozzle D, and having waste-pipe F, substantially as and for the purpose described and shown.
